ARRANGEMENT FOR CONTROLLING TUBE SENDERS.

Application filed February 16, 1925, Serial No. 9,549, and in Germany December 5, 1923.

Our invention relates to means for controlling tube senders in signalling wherein use is made of radio apparatus, and has for its object to provide such an arrangement which 5 will effectively control the sending tubes to give the desired signal and yet will not cause said tubes to be destroyed through undue heating when signals are not being sent. This invention is principally useful when 10 the plate current is derived from an alternating current source and then suitably rectified since the voltage regulation of such a plate supply arrangement is inherently poor. 15 Other objects will be apparent from the following description and claims when considered with the accompanying drawing, in which—

Figure 1 shows a form of our invention 20 using a self-excited controlling tube and a separately excited controlling tube for transmission. Fig. 2 shows an arrangement similar to Fig. 1, and Fig. 3 is a modification of the drawing as shown in Fig. 1 applying the 25 idea of the invention to telephone work.

In arrangements in which a tube transmitter is fed by a second self-excited tube transmitter, the operation of keying in the case of telegraphy work, and the modulation 30 in telephony can be accomplished in various ways. The self-excited tube transmitter is an oscillation generator, while the controlled tube transmitter is an amplifier. In the majority of cases action is brought upon the 35 grid of the self-excited or of the amplifier tube for the reason that the requisite keying or modulating energy is small.

In what way the grid keying or the modulation should best be accomplished is well 40 known, and similarly well known is the keying or the modulation of the grid of a separately controlled tube.

In both kinds of action, however, certain 45 inconveniences manifest themselves which are observed in and are peculiar to this combination of a separate amplifier tube and a self-excited tube. These difficulties shall first be discussed in the following before the idea underlying the invention is further discussed.

According to the old methods, the arrangement was provided with a self-excited transmitting tube, in which the self-excited tube

gets its self-excitation by means of a three point connection on an oscillation circuit. 55 Coupled with this oscillation circuit is a second oscillation circuit to the condenser of which the grid member of the second tube is connected. This second tube is arranged to feed its energy upon an antenna in any well 60 known manner.

For the purpose of keying or modulating it has been customary to connect the grid of the self-excited tube to its oscillation circuit through a capacity and to the filament by 65 way of a choke coil and a modulating or keying device. If, when the oscillations fed to the grid of the separately excited tube are subject to marked decreases, or when they stop entirely (as during keying and speech 70 intermissions), it is well known that there flows in the tube an idle current which tends to heat the anode. The tube being unloaded at this time, the anode voltage is higher than during load. This is a phenomenon that can 75 not be avoided when the plate current is derived from rectified alternating current.

This disadvantage may be rendered harmless if the grid of the separately excited tube is 80 acted upon or influenced by a keying or modulator device operating directly on the said tube instead of on the self-excited tube. In such a case the grid of the self-excited tube would be connected directly with the tube oscillation 85 circuit and the grid of the separately excited tube would be connected with its oscillatory circuit by way of condenser and with the filament by way of the choke coil and a keying or modulation device.

If, by the latter method, the direct grid 90 potential of separately excited tube is compensated, neutralized or greatly diminished, the tube oscillation circuit will be subject to less damping. In other words, more energy will be taken away from the oscillatory circuit of the first transmitting tube. If the first transmitting tube and its oscillatory circuit were previously properly coupled, the anode alternating current will then be caused to drop in the same, with the consequence that 100 the heating of the anode is raised in that tube. If, in this scheme, both tubes are fed from the same anode voltage source, i. e. by rectified alternating current, the voltage of 105 which will greatly increase when the load is taken off the second transmitting or sep-

arately excited tube, it will be seen that the heating of the first transmitting or self-excited tube is apt to assume inadmissibly high values.

5 Hence, it seems necessary that the grid current of both tubes be simultaneously interrupted or diminished during the intermissions in key or speech work. This could be done, e. g., by having distinct keying and 10 modulator devices for the two tubes. Yet, apart from the greater outlay in equipment, such an arrangement would be unsuitable, because two keying and modulating devices could be operated in exact synchronism only 15 with great difficulty.

Now, the present invention obviates all of the said difficulties by means of a method according to which the grid discharge circuit of the self-excited tube and the separately 20 excited tube transmitters are simultaneously keyed or influenced by a modulator device. An arrangement of the kind embodying means to practice this method consists in having the grid discharge circuit of the self- 25 excited transmitter and the separately excited transmitter provided with a common branch containing the keying or the modulating device, and which, as a consequence, influences both grids simultaneously.

30 The arrangement according to this plan has been so chosen that the grids are blocked against one another and the common branch with reference to the grids by the aid of high frequency blocking means. Fig. 1 illustrates by way of example in what way the 35 idea could be carried into practice. The grids of tube *a* and *b* are blocked against the circuits *c* and *d* by the aid of condensers *f* and *f'* in a capacitive manner, while being 40 interconnected by way of high frequency choke coils *g* and *g'*. The common point *k* of the choke coils is connected with the cathode pole *l* common to both filaments by way of the keying or modulating device *h*. 45 In order to safeguard point *k* against all high frequency potentials, a path *s* for the current is created parallel with reference to *h* which is impassable for the direct current, said path offering as low a resistance as 50 feasible to the flow of high frequency current.

Fig. 2 shows the application of the idea underlying the invention to telegraphy work. The keying organ is the telegraphy 55 key *h*, a condenser *s* being connected conveniently in parallel thereto.

Fig. 3 shows the application of the idea to telephony work. The modulator means consists of the tube *t* whose filament, in well 60 known manner, is connected with the grids of the transmitter tubes *a* and *b* whereas its anode is put in conducting connection with the filaments of both tubes. Parallel relative to the anode and cathode of the modulator tube *t*, there is again arranged in con-

venient manner the condenser *s*, while the speech modulation is produced by way of speech modulating transformer *n*.

Having described several embodiments of our invention, we are entitled to all modifications thereof as fall fairly within the scope of the following claims:

1. An arrangement for wireless telegraphy and telephony comprising a self-excited controlling tube and a separately excited controlled tube for transmitting, a modulating means adapted to simultaneously control the grid circuit of each tube, a branch circuit common to the grid circuit of each of said tubes, said modulating means being contained in said branch circuit, and means in the grid circuit of each tube for blocking the grids against one another with respect to high frequency currents.

2. An arrangement for wireless telephony and telegraphy comprising a self-excited controlling tube and a separately excited controlled tube for transmitting, means by which the grid circuits of each of the said tubes are simultaneously subjected to modulation whereby heating of the anode members of each tube may be minimized at the "no load" period, a branch circuit common to each of the said grid circuits, said means for producing modulation being contained in the said branch circuit, means to block the grids members of said tubes against one another with respect to high frequency currents, said blocking means comprising high frequency choke coils inserted in the connection between the two grid members, and a high frequency path arranged in parallel to said modulating device.

3. In an arrangement for wireless telegraphy and telephony an oscillator and an 105 amplifier tube, a connection between the grid elements of each of said tubes, said connection being made by way of a high frequency choke coil, a connection between the cathode members of said tubes, a branch 110 circuit common to each tube between the said grid and cathode connections, a modulating device arranged in said common branch circuit and a condenser arranged in parallel to said modulating device.

4. In an arrangement for wireless telephony, a controlling and a controlled tube for transmitting, high frequency choke coils through which the grid members of said transmitters are connected, a connection between the cathode and members of said tubes, and a third connection by way of a modulating device having one terminal connected between the said choke coils and the second terminal connected to the cathode 120 connection, said modulating device comprising a third tube to which a modulation means is joined.

5. In an arrangement for wireless telephony, a controlling and a controlled tube 130

- for transmitting, a connection between the grid elements of said tubes, said connection being formed through high frequency choke coils whereby the said grids are blocked with respect to high frequencies relative to each other, a connection between the cathode members of the said tubes, a branch circuit common to each of said tubes arranged between the grid and cathode connections, a modulating device for simultaneously subjecting the grid of each tube to modulation located in said branch circuit, said modulating device comprising a third tube having its cathode member connected to the grid connection point of the branch circuit and ¹⁵ its anode member connected to the cathode point of the branch circuit, a modulating circuit having one end connected to the grid member of said modulating tube and its opposite end connected to the grids of the said ²⁰ transmitting tubes, and a condenser between the cathode and anode of said modulating tube.
